UNITED STATES PATENT OFFICE.

DANIEL M. WINANS, OF BINGHAMTON, NEW YORK, ASSIGNOR TO THE BREWER-TITCHENER CORPORATION, OF BINGHAMTON, NEW YORK, A CORPORATION OF NEW YORK.

DETACHABLE LIGHT FOR VEHICLE-CURTAINS.

1,363,702.

Specification of Letters Patent. Patented Dec. 28, 1920.

Application filed February 5, 1919. Serial No. 275,075.

To all whom it may concern:

Be it known that I, DANIEL M. WINANS, a citizen of the United States, residing at Binghamton, in the county of Broome and 5 State of New York, have invented certain new and useful Improvements in Detachable Lights for Vehicle-Curtains, of which the following is a specification.

This invention is an improvement on the 10 detachable lights for vehicle curtains set forth in my applications Ser. Nos. 204945 and 243414.

My object is to simplify, lighten, strengthen, and cheapen the frames or rings 15 which hold the "light," provide them with smooth, flat, broad, continuous flanges for clamping the fabric and the "light" with firmness and yet with sufficient springiness to adapt them to variations in the thickness 20 of the glass, prevent rattling without requiring undue pressure, and to effect a water-tight joint.

The invention consists in a frame and back-ring of sheet metal, preferably either 25 stamped or die-cast, both of substantially the same cross-sectional shape, nested one within the other, each having an inner, continuous, smooth, and relatively broad flange, the frame and back-ring being detachably 30 fastened together by suitable means, preferably improved connections, and clamping the fabric between them, the "light" being firmly held between the flanges.

In the following description I have disclosed certain forms the invention may assume but it is to be understood that such disclosure is illustrative, and not restrictive, of the invention, as other modifications may be resorted to.

40 In the accompanying drawings:

Figure 1, is a view of the outer face of a portion of the outer frame;

Fig. 2, is a view of the inner face thereof;

45 Fig. 3, is a view of the outer face of a portion of the back-ring;

Fig. 4, is a view of the inner face of the back-ring;

Fig. 5, is an enlarged horizontal section 50 of a portion of the complete light;

Fig. 6, is a view like Fig. 5, showing a modified fastening;

Fig. 7, is a view like Fig. 5, showing a flush-headed fastening; and

Fig. 8, is a view like Fig. 5, showing another modified fastening.

A portion of the curtain of an automobile is shown at 1, and the pane or light at 2, the latter being illustrated as of bevel plate glass.

The outer frame 3 and inner frame or back-ring 4 are of substantially the same shape in cross-sectional form. They are of sheet-metal, formed either by stamping or by die-casting. As shown, they are preferably arched in cross-sectional shape. This enables the frame 3 and back-ring 4 to be nested and thus mutually strengthen and reinforce each other while also providing a wide bearing or clamping surface where the 70 curtain 1 is clamped between them, minimizing damage to the curtain and insuring a very firm grip thereon and no danger of displacement of the frame, back-ring, and light. The frame and back-ring are, respectively, provided with inner, continuous, smooth, broad, flat clamping flanges 5 and 6 which bear on opposite sides of the light. The curtain preferably extends to the inner edge of the flange 5.

The inner or back-ring 4 may be formed on an arc of slightly shorter radius than the outer frame 3, to permit proper nesting.

When the frame and back-ring are clamped on the pane or light, the relative 85 thinness of the material enables them, particularly the back-ring 4, to yield, due to the inherent resiliency of the material. Consequently, the inner portions of said frame and back-ring may spread slightly, as shown 90 in Figs. 5 to 8, and the clamping action on the light 2 is a firm, yet sufficiently yielding one to compensate for variation in thickness of the glass, and to prevent rattling without requiring undue pressure, while also 95 making the joint with the light watertight.

The relatively broad, flat clamping flanges 5 and 6 have a decided advantage over a sharp or sheared edge in that they neither 100

cut the curtain nor start cracks in the glass light. Where a sharp or sheared metal edge directly contacts with glass, there is a tendency for the microscopic teeth on the sharp edge to seek microscopic defects in the glass and, by the movement and jar on the curtain, to start cracks. Plate glass being heavy, it exerts many jerks on an automobile curtain while the car is in motion and such tendencies are well-known.

The frame 3 and the back-ring 4 while shown as circular, may be of any shape. Said frame and back-ring while preferably arched in cross-sectional form, need not be formed on true arcs and a wide variation of cross-sectional shape could be resorted to, the main object being to nest the back-ring within the frame and to form them of relatively thin metal, as by stamping or die-casting.

The frame and back-ring may be detachably fastened together by any of the fastening means of Figs. 5, 6, 7, 8. In each instance, there is a screw and a fastening nut, the screw passing through holes in the frame and back-ring, and the nut being located within the back-ring.

In Fig. 5, the screw 7 is in the form of a stud passing through a hole 8 in the frame and having a shoulder 9 and headed down on the frame at 10, thus being permanently carried by, and self-contained with the frame. In this fastening the fact that the screws are carried by the frame, facilitates the assembly of the frame, back-ring and curtain, for the application of the nut 11. The back-ring may have the opening 12 somewhat larger than the screw to permit a slight relative adjustment of the frame and back-ring.

In Fig. 6, the screw 7^a passes freely through the holes 8 and 12^a and is completely detachable from the frame and back-ring.

In Fig. 7, the metal surrounding the hole 8 is pressed in and the screw 7^b passes through said hole and hole 12^b and its head 10^a is sunk flush with the outer face of the frame so as to be invisible. The screw may be upset at 9^a so that it will be permanently attached to the back-ring.

In Fig. 8, the screw 7^c passes freely through holes 8 and 12^c and is completely detachable. A continuous plate 13, corresponding to the outline of the back-ring

bears on the latter and is provided with a slotted-headed nut 11^a which engages the screw.

In all forms, the curtain has holes 14 for the passage of the screws.

Preferably, the curtain is provided with some suitable adhesive 15 which causes the back-ring to adhere thereto. Due to this, the frame may be removed, without taking off the back-ring, the light taken out, and the frame re-applied and secured when it is desired to have a circulation of air through the curtain as, for instance, in mild or hot weather.

What I claim is:

1. In a light for vehicle curtains, inner and outer cross-sectionally-bowed sheet metal frames, nested within each other with their bowed parts facing in the same direction, and releasable screw and nut fastenings connecting the bowed parts of said frames for holding said frames in nested relation with their inner marginal parts free to spring or flex, the curtain being entered between their outer parts and gripped between the frames, and the marginal part of the pane entered between the inner marginal parts of the frames and held by said springy inner marginal parts.

2. In a detachable light for vehicle curtains, inner and outer separable frames of relatively thin, springy material bowed in cross sectional shape and detachably nested within each other so as to grip the curtain, said frames having corresponding inwardly projecting flanges at their inner margins, means for securing the bowed parts of the frames together to clamp said bowed parts, and a light whose marginal portion is held by and terminates between said flanges.

3. In a detachable light for vehicle curtains, inner and outer separable frames, a curtain secured to one of the frames by an adhesive so that said frame will remain in position when the other frame is removed, and fastening means for detachably securing the frames detachably together.

4. In a curtain light, a frame having fabric-engaging and pane-holding members, means for clamping said members together, and a finishing member secured to said clamping means and covering a face of the frame.

In testimony whereof I affix my signature.
DANIEL M. WINANS.
